HEM GUIDE

Leonard G. Johnson, Fergus Falls, Minn.

Application January 8, 1951, Serial No. 204,901

1 Claim. (Cl. 33—2)

1

This invention relates to new and useful improvements in marking devices and the primary object of the present invention is to provide a hem guide and gauge for garments.

Another important object of the present invention is to provide a hem gauge for use in pinning a hem before basting, such as a skirt hem, curtains, or other such edges that require finishing.

A further object of the present invention is to provide a hem guide so constructed as to permit the same to be retained in front of a sewing machine needle as the hem is being sewed to provide a constant check to the accuracy of the hem.

A still further aim of the present invention is to provide a hem guide having a finger grip and a smooth undersurface to prevent the marring of the sewing machine, sewing table or the snagging of materials upon which the guide is disposed.

Yet another object of the invention is to provide a hem guide including a scale and a slide member that is spring retained adjusted with respect to the scale whereby a chalk may be placed adjacent the scale and in alignment with the slide.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view showing the present invention in use; and

Figure 2 is a transverse vertical sectional view taken substantially on the plane of section line 2—2 of Figure 1.

Referring now to the drawings in detail, wherein for the purpose of illustration is disclosed a preferred embodiment of the present invention, the numeral 10 represents an elongated flat panel having an upturned longitudinal edge forming a finger grip 12. The other longitudinal edge 14, of the panel 10 is beveled and is provided with a scale 16 thereon.

The upper face of the panel 10 is provided with an elongated dovetail groove 16a that parallels the bevel edge 14. A traveling member 18 overlies the groove 16a and includes a pointer 20 that extends transversely across the bevel edge 14 and which overlies the scale 16.

A fastener 22 extends through the traveling member 18 and its lower end passes through a concavo-convex spring 24 and is flattened against the concave surface of the spring 24. The convexed surface of the spring 24 yieldingly bears against the dovetail edges or inclined side walls 26 of the groove 16a to yieldingly urge the undersurface of the member 18 against the flat upper

surface of the panel 10 and hence the member 18 longitudinally adjustably upon the panel.

In practical use of the present invention, the flat undersurface of the panel 10 is placed upon a garment or the like G and the traveling member is moved to a desired position in order to indicate the length of hem. Then, the operator will mark the garment G by a chalk or the like C as the panel 10 is manually moved upon the garment by the user grasping the finger gripping portion 12.

Due to the flat and smooth undersurface of the panel 10, the panel will not effect a marring of the sewing machine or a snagging of the garment or material G. The inclination of the pointer 20 and the bevel edge 14 will permit the device to be extended to the sewing machine needle as the hem is being sewed thereby providing a constant guide or check to the accuracy of the hem.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

Having described the invention, what is claimed as new is:

1. A hem guide comprising an elongated flat panel having an upturned edge forming a finger grip, said panel having a longitudinal dovetail groove and a scale thereon alongside of said groove, a traveling member overlying the groove and resting upon the upper surface of the panel, said member including a pointer overlying the scale, and a concavo-convex spring positioned in said groove and secured to the under surface of said member, the convex surface of said spring yieldingly bearing against the dovetail edges of said groove and urging the member against the panel.

LEONARD G. JOHNSON.
